United States Patent Office

Des. 225,486
Patented Dec. 12, 1972

225,486

DRINKING STRAW

Philip D. Bart, Monsey, N.Y.
(3070 NE. 43rd St., Fort Lauderdale, Fla. 33306)

Filed Apr. 5, 1971, Ser. No. 131,582

Term of patent 14 years

Int. Cl. D7—99

U.S. Cl. D94—3

FIG. 1 is a front view of a drinking straw showing my new design,

FIG. 2 is a right side view thereof,

FIG. 3 is a left side view thereof,

FIG. 4 is a top plan view thereof, and

FIG. 5 is a bottom plan view thereof.

I claim:

The ornamental design for a drinking straw, as shown.
